UNITED STATES PATENT OFFICE.

HERBERT M. FRIENDLY, OF CHICAGO, ILLINOIS.

AUTOMATIC TELEPHONE SYSTEM.

Application filed October 27, 1920, Serial No. 420,016. Renewed June 7, 1926.

The present invention has for its broad objects, the improvement of telephone systems in general and more particularly automatic and semi-automatic telephone systems, looking toward lowering maintenance costs, and also the affording of operative conveniences to users which have been heretofore unknown.

The invention in the specific form chosen 10 for the illustration herein, contemplates a so-called two-wire common battery automatic telephone system as has been widely used, the present invention necessitating novel departures from equipments heretofore 15 known, in attaining the new objects, while retaining certain operative functions which are known.

In overcoming limitations of connector switches as heretofore used in automatic 20 telephone systems, the present invention contemplates the following and other novel objects:

(a) Means, whereby when the connector has completed its first ordinate or primary 25 movement, (as by stepping vertically responsive to the next-to-last digit of the called number being sent from the impulse sending device) the calling party will be audibly apprised that the connector responded normally and is ready to receive the next series 30 of impulses to drive the connector wipers by a secondary movement to reach the called bank number. Further, to similarly apprise the calling party when the wipers have re- 35 sponded normally to the final series of impulses by moving co-ordinately in numerical correspondence therewith and stopped preparatory to extending the calling line to the called bank number.

(b) Means whereby in the event a dead 40 or unconnected line is inadvertently called and the connector wipers seize the corresponding bank contacts, a specific tone will be automatically applied and projected back from the connector, audible to the calling party to indicate that the line called is dead or unconnected.

(c) Means, whereby in the event an out-of-order line (one open to signaling current 45 for example) is called and the connector wipers seize the corresponding bank contacts, a specific tone will be automatically applied and projected back from the connector, audible to the calling party.

(d) Means, for reducing or practically 50 suppressing the audible disturbance hereto-

fore experienced from a reversal of current over the calling line when the called party responds, such reversal being usually for supervisory use, or message meter or coin 60 device operation. This reducing or suppressing is preferably accomplished by attenuating the strength of current projected towards the calling party by the inclusion of a resistance in the battery supply path 65 before reversal and then augmenting the strength to the normal value after the reversal, by the exclusion of the resistance. The current direction transition being less abrupt than heretofore the audible disturbance 70 is thus less than heretofore wherein the transition has been effected in one positive step.

(e) Means, for audibly apprising the calling party that the called party, after responding, has hung up his telephone receiver and that will similarly apprise the called party that the calling party has hung up his telephone receiver. That is to say, 75 if one party to a completed telephonic connection hangs up his telephone receiver, the other party is audibly apprised of the fact. 80

The foregoing, and other novel objects of the present invention, and the invention itself will be understood from the following 85 description thereof, together with the accompanying drawing.

The calling automatic telephone set P leads over line conductors 2 and 3 to pre-selector K located at the exchange. The pre-selector K has access to a plurality of first selectors, one only, N, of which is diagrammatically shown reached over line conductors 4 and 5 and private conductor 6. The first selector N has access to a plurality 90 of connectors (directly or through second selectors), one connector only being shown schematically, reached over line conductors 7 and 8 and private conductor 9.

The calling automatic telephone set P is of the usual series type having a sending device 100 10 of the general class as shown in British patent to Dicker, No. 29,654 of 1910. The pre-selector K is of the general class as shown in U. S. patent to Lamb No. 1,193,160 105 granted August 1, 1916. The first selector N is of the general class as shown in U. S. patent to Keith et al. No. 815,321, granted March 13, 1906, of course modified in mechanical and circuit details to 110 operate on the well-known so-called two-wire principle. The connector is of the general

class as shown in U. S. patent to Keith et al. No. 815,176, granted March 13, 1906, of course modified in mechanical and circuit details to operate on the well known so-called two-wire principle and to embody the present invention. The called telephone set Q is similar to P and is shown as a called telephone on bank contact set twenty-two, reached over line conductors 11 and 12. Conductor 13 leads to the winding of cut-off relay 14, of a pre-selector similar to K, so when the set Q is called by the connector wipers 15 and 16 seizing bank contacts 17 and 18 leading to the line conductors 11 and 12 respectively and private wiper 19 seizes and grounds bank contact 20 leading over conductor 13 to free terminal of winding of cut-off relay 14, the operative windings of the pre-selector on the called line will be 20 associated in the well known way. The conductors 11, 12 and 13 are common to other bank contacts before connectors reachable by the same coordinate operation of the connector wipers.

To simplify the drawings and description, the battery and ground are shown as independent sources throughout, wherever applied but it is to be understood that the system is of the common battery type. In the description, when a circuit is traced to a winding, the opposite terminal of which is shown applied to grounded battery or to ground, the described circuit is to be considered as traced to ground through the winding and battery, or direct to ground as indicated.

Tone sources are indicated designated, "Busy tone," "Dead line tone," "Out-of-order tone," "Cut-in tone" and "Last-party tone" respectively. The said respective tone sources are represented conventionally as an inductorium, one winding of which has one terminal applied to grounded battery and the other terminal thereof applied to ground through an interrupter device adjustable to the desired period. The secondary winding will apply induced potential from ground to the receiving conductor leading to the connector shown and to other connectors in common therewith. The tones are thus indicated as "ground seeking," and the receiving conductors therefrom will be referred to as if they constituted a tone source in themselves.

In elucidation of the present invention, the performance of the equipments will be detailed under different assumed operative conditions.

Assuming a call from telephone P to telephone Q, upon receiver 21 being removed from the hookswitch to initiate the call, pre-selector K will seize the trunk leading to the first selector N. Further assume the first selector N to be idle, and therefore conductor 6 to be ungrounded. Only the first bank level of the selector N is shown

and the first set of bank contacts thereof lead to the connector. Thus, upon the calling party sending the digit "1" by means of sending device 10, effecting one open impulse, the selector N will step its shaft and 70 the wipers thereon to the first vertical position and there rotate-in to and seize the first set of bank contacts from which conductors 7, 8, and 9 lead to the connector. The foregoing functioning of the pre-selector, and of 75 the first selector seizing a set of conductors, (or, in the parlance of the art, a trunk) leading to an idle connector is well known.

The connector being now seized telephone set P will derive exciting current from upper winding terminal of relay A, resting contact 23 and make-before-break contact spring 24 of relay D, conductors 8, 5 and 3, through telephone set P, conductors 2, 4 and 7, make-before-break contact spring 25, resting contact 26, conductor 27, armature 28 and resting contact 29 of relay G, conductor 30 to lower winding of relay A. Relay A will actuate, followed by dependent relay B due to ground on its armature 31 being applied to working contact 32 and to the winding of said B. Relay B has a slow release characteristic, so lapses of exciting current of the period of call-selecting impulses will not be of long enough duration to cause it to deactivate. However, it will not sustain actuated over prolonged lapses, such as ensue upon hanging the receiver 21 upon the hookswitch for a moment. Incident to relay B actuating, its armature 33 will apply ground to its working contact 34 and over conductor 35 to release trunk 36 leading to conductor 9 which ground will sustain the selector and pre-selector in a manner well known in the art.

Upon the second digit "2" being sent from sending device 10, effecting two open impulses, relay A will deactivate and reactivate two times resultant thereto, relay B remaining actuated. Armature 31 in retracting twice applies two ground impulses to its resting contact 37 and to attracted armature 38 and its working contact 39, conductor 40, resting contact 41 and armature 42 of relay H, conductor 43, series winding of relay C 110 to the winding of the vertical magnet, (designated Vert. M.) and to the contact engaged by side-switch arm 44 in the first position to grounded battery, the said vertical magnet attracting its armature two times, thereby 115 stepping the connector shaft carrying wipers 15, 16 and 19 two vertical steps so they register in line with the second bank level which contain bank contacts 17, 18 and 20 respectively. Relay C has a slow-release characteristic, so when it actuates from the current applied to the vertical magnet through its winding it will sustain over the lapses and for its period after the last lapse begins incident to the closure after the sec- 120 125 130

ond open impulse is sent from sending device 10. When relay C actuates it applies ground on its armature 45 to its make-before-break contact 46 and over conductor 47 to the winding of the private magnet (designated Priv. M.) causing it to attract its armature preparatory to admitting the side switch arms 44 and 48 to move into the second position respectively. Electrical contact 10 armature 49 on the private magnet engages its contact 50 incident to the energization of the private magnet, applying a supplemental ground on the release truck 36. When armature 45 of relay C retracts its period after 15 the termination of the impulse series and the private magnet is de-energized, side switch wipers 44 and 48 move into the second position respectively, wiper 44 applying grounded battery to contact 51 during a period of its passage from the first to the second position.

When the ground-seeking battery is applied from wiper 44 to contact 51 and over conductor 52 to free winding terminal of 25 slow-releasing relay 53, causing the said relay 53 to actuate and attract its armature 54 into engagement with contact 55, and for the deactuation period of the said 53 thereafter, the ground seeking cut-in tone source is applied over conductor 56, working contact 55, engaging armature 54, conductor 57 to line conductor 58 leading through condenser 59 to conductor 60, conductors 7, 4 and 2, telephone set P, conductors 3, 5 and 61, through condenser 62, conductors 63 and 64 to free terminal of upper winding of relay D. Also over a derived path from conductor 8, contact spring 24, resting contact 23 to free terminal of upper winding of relay A. This tone will be audible to the calling party during the period of actuation of relay 53 and will index that the connector functioned normally responsive to the second digit series sent and further that the connector is in 40 readiness to receive the third or final digit series, the battery on wiper 44 being now applied to the left or energy terminal of the rotary magnet (designated Rot. M.). This function was adverted to in paragraph "a" 45 at the outset.

Upon the third digit "2" being sent from sending device 10, effecting two open impulses, relay A will deactuate and reactuate two times resultant thereto, relay B remaining actuated as at its primary closing incident to the initiation of the call. Armature 31 in retracting twice, as before, applies two ground impulses to its resting contact 37 and to attracted armature 38 and its working contact 39, conductor 40, resting contact 41 and armature 42 of relay H, conductor 43, series winding of relay C, conductor 65, armature 66 and its resting contact 67 of relay J to free winding terminal of the rotary magnet and to contact engaged by side-

switch arm 44 in second position, to grounded battery; the said rotary magnet attracting its armature two times, thereby stepping the connector shaft carrying wipers 15, 16 and 19 two rotary steps so they 70 engage the second set of bank contacts 17, 18 and 20 respectively. At the time of energizing the rotary magnet, relay C will actuate and cause the private magnet to attract its armature as when the vertical magnet was caused to function. That is, it actuates incident to the first impulse and remains in the actuated position until the expiration of its period after the closure of the sending device following the transmitting of the 75 second open impulse. Again, upon the deactuation of relay C the private magnet will retract and admit the sideswitch wipers 44 and 48 to move into the third position respectively, wiper 44 applying grounded battery to contact 68 during a period of its passage from the second to the third position.

When the battery is applied from wiper 44 to contact 68 and over conductor 52 (contacts 51 and 68 being common to conductor 90 52) to the winding of the slow-releasing relay 53, relay 53 is caused to function as before described and apply a tone, audible to the calling party. In this instance the tone will index that the connector has engaged 95 the called set of bank contacts. The connector will seize the engaged set if idle and thereafter project a specific tone to the calling party indexing the called line is just being signaled upon, or project specific tone 100 to the calling party indexing the called line is busy; is dead; or is open, and therefore, in the latter instance "out-of-order."

Assuming that the called line is normal and therefore no ground exists on private bank contact 20 engaged by wiper 19. When the sideswitch wipers 44 and 48 have reached the third position respectively ground on sideswitch contact 69 is applied to the upper winding terminal of relay H through sideswitch arm 48, conductors 70 and 71. Also, ground is applied from conductor 70 through winding of relay E and conductor 72 to wiper 19, engaged bank contact 20, conductor 13 to the winding of cut-off relay 14, disassociating the operative windings of the pre-selector on the called line. The bank contact 105 20 being now grounded will guard the said called line against intrusion, as will be seen presently, because thereof. Relay E actuates responsive to the deriving of current through it from the winding of the cut-off relay 14 to the grounded sideswitch contact 69. Also, the battery on sideswitch wiper 44 applied to the side-switch contact 73 and 110 over conductor 74 is applied to the lower winding terminal of relay H. Relay H thus has ground on its upper winding terminal and battery on its lower winding terminal, causing it to actuate and apply its armature 115 120 125 130

75 to its working contact 76 and its armature 77 to its working contact 78.

A circuit path may now be traced from ground seeking-alternating current source 79, 5 conductor 80, lower winding of relay G, its resting contact 81 and its make-before-break contact 82, conductor 83, resting contact 84 and armature 85 of relay F, armature 77, working contact 78, wiper 15, bank contact 10 17, line conductor 11, signal device of telephone set Q, line conductor 12, bank contact 18, wiper 16, working contact 76, and armature 75 of relay H, armature 86 and resting contact 87 of relay F and to the free terminal 15 of the inside winding of the latter relay. Relay F is so mechanically designed as to not be operatively susceptible to the constant alternating current from the source 79, or to the interrupted alternating current from 20 the source 88, but to be operatively susceptible to direct current as would ensue from the battery at the live terminal of the inside winding of relay F through the receiver of telephone set Q, if off the hook, to ground 25 through said source 79.

Relay G is so mechanically designed as to be operatively susceptible to the alternating current from source 79, applied over the described path through the signal device of 30 the telephone set Q; the said signal device including a condenser for rendering the signal path opaque to direct current but transparent to the alternating current from sources 79 and 88. Thus, relay G will actuate 35 following the actuating of relay H. As will be clear presently, the office of relay G is to test the transparency of the signal current path, and if the path is intact, (indicating a normal condition) the relay will 40 actuate; otherwise it will not.

At this juncture relays H, E, G, B and A are actuated. So, upon the actuation of relay G ground derived through out-of-order tone source applied over conductor 45 89 to contact 90 and engaged armature 91 of relay E, armature 92 and resting contact 93 of relay F, armature 94 and working contact 95 of relay H, conductor 96, armature 97 to working contact 98 and to the upper winding 50 of relay G, locks relay G. Armature 94 is preferably adjusted to engage contact 95 last of the contacts on relay H so the relay G can attract armature 97 from resting contact 99 before said 95 is engaged, to prevent 55 a false tone being applied to conductor 57, audible to the calling party.

Incidental to the actuation of relay G its armature 28 is attracted from its resting contact 29 thus removing the short circuit 60 from the resistance 100 and causes it (the resistance 100) to be included into the circuit including the lower winding of relay A and the calling telephone set P, thus attenuating the current flow exciting the 65 receiver 21.

Incidental to the shaft stepping off-normal responsive to the first vertical impulse off-normal springs 101 and 102 will engage grounded spring 103, (which latter spring may be termed "off-normal ground") and 70 spring 104 will engage spring 105. Thus, when the springs 101 and 103 engage, ground on spring 103 is applied to spring 101, conductor 106, armature 107, and its resting contact 108 of relay F, conductor 109, winding of relay 110 through interrupter 111 to grounded battery. The relay 110 will actuate periodically in conformance with the establishment of the described circuit path through the interrupter 111. When the relay 110 actuates signalling current from source 88 on working contact 112 is applied to engaging armature 113, lamp 114, conductor 115, armature 116, make-before-break contact 82, conductor 83, resting contact 84, 80 armature 85, armature 77, working contact 78, wiper 15, bank contact 17, line conductor 11, signal device including the condenser thereof in telephone set Q, line conductor 12, bank contact 18, wiper 16, 85 working contact 76, armature 75, armature 86, resting contact 87, through inside winding of relay F to grounded battery. Since the alternating (or other variable type of current operatively effective to relay G but not operatively effective to relay F) current source 79 is applied only briefly for test purposes it is not necessary that its character shall be such as to be effective to the signal device in telephone set Q in fact it may be advantageous under conditions of the use of quickly responsive signal devices for example, for the current from source 79 to be non-effective to the said signal device to prevent a false actuation, particularly in case the seizure of the line by the connector is at a time when the relay 110 is deactuated and therefore not ready to apply current from source 88 in lieu of that from source 79 immediately upon relay G actuating. 100

Upon the receiver at the called telephone being removed, thus closing a conductive circuit between the line conductors 11 and 12 including the telephone set Q, the grounded battery at the live terminal of the inside winding of relay F will be applied over the path described for the signaling current projected from source 88 to ground through said signaling source if the relay 110 is actuated, and to ground at resting contact 117 115 in lieu thereof if relay 110 is normal, that is, in the latter instance, during the "silent periods."

The inside and outside windings of relay F being wound inductive to the relay core 125 are incidentally mutually inductive. Therefore, the signaling current projected out over the line conductor 11 through the signal device in the telephone set Q and back over line conductor 12, through the inside 130

winding of relay F to grounded battery will induce a ground-seeking current, audible to the calling party, in the mutually inductive outside winding of said F. The induced current in the outside winding of relay F will be conducted to conductor 118 and through lower winding of relay D to conductor 58 and thence over the path including the calling telephone set P described in connection with the cut-in tone applied from conductor 57. The calling party discerns a tone, indicative that the signaling current is applied to the line over the normal signaling path and that said current returns to the connector normally. Upon the called telephone being responded-to by the receiver thereof being removed from the hookswitch, a conductive circuit is established through the receiver between the line conductors 11 and 12.

As set forth, relay F will actuate under the latter conductive circuit condition, whereupon armature 119, which receives off-normal ground from spring 102 over conductor 120, engages working contact 121 which leads to the outside winding of relay F and to conductor 118, causing said F to now completely actuate and lock, and so remain until the springs 102 and 103 disengage incident to the connector shaft returning to normal.

Incidental to the actuation of relay F conductor 63 leading to working contact 123 is engaged by armature 86 in lieu of its resting contact 87, and conductor 58 leading to the working contact 124 is engaged by armature 85 in lieu of its resting contact 84. The described and traced incoming circuit from calling telephone set P is now in telephonic relation with the called telephone set Q over the described and traced signaling circuit, the receivers of both calling and called sets being off the hookswitch. Further, the upper terminal of the lower winding of relay D which leads to conductor 118, and which is normally open at contact 121 of relay F now completes the battery supply circuit to the called telephone set Q. That is to say, the battery potential applied through upper winding of relay D to conductor 63 now produces a current flow out over the heretofore described path through the telephone set Q and back over conductor 58 and through the lower winding of relay D, conductor 118, working contact 121, armature 119, conductor 120, spring 102 to "off-normal" ground on spring 103. Relay D will actuate by reason of this energized circuit including its windings. Armature 124 will engage make-before-break contact 24, disassociating resting contact 23. Also, armature 125 will engage make-before-break contact 25, disassociating contact 26. This transition will reciprocate the relationship of the line conductors

7 and 8 with respect to the lower and upper winding of relay A respectively, and consequently the direction of current flow through the calling telephone set P. Relay G being in its actuated position the now-included 70 resistance 100 suppresses the current flow through said set P consistent therewith, regardless of the direction of current flow. Relay G has a slow release characteristic and thus remains actuated a period after 75 its described locking circuit is opened by the disengagement of resting contact 93 by the attraction of armature 92. This opening of the locking circuit occurs coincident with the response at the called telephone set Q 80 as set forth, followed by the reversal of current incident to the actuation of relay D described. Then, after the period of relay G, whereupon it deactuates, the resistance 100 is short-circuited and therefore excluded as an obstruction in the current supply path to calling telephone set P, augmenting the current strength to normal service value. Thus, the reversal of current 85 takes place during the time the current supply is attenuated and therefore causes a minimum of disturbance to the receiver and the current strength is at its normal value during the period of telephonic service. 95

Assuming that conductor 11 or conductor 12 is open, as may be due to a defective line condition, or because a workman has opened one or both of them at the cross-connecting frame, for example, because of 100 a defective condition of the line. That is to say, in the latter instance the workman may have disconnected the line so calling parties cannot reach it because of its defectiveness or because the defectiveness is 105 of such nature (a cross, or a ground on the live side, for example) that it would cause confusion by falsely initiating a call, in effect. Heretofore, such conditions of faulty lines have caused confusion and unsatisfactory operation. It has been a practice in certain exchanges to simply open the line conductors on the cross connecting frame, at the heat coil and protector terminals, for example. Then, when the calling connector 110 seizes the incapacitated line the calling party will fail to receive the reverting tone indicative that the line is normal, as hereinbefore fully discussed, and conclude the line is out of order. Again this condition 115 of not receiving the reverting tone may be occasioned because of erroneously calling a dead or unconnected line, either due to inadvertence on the part of the calling party or due to a faulty switch operation. So 120 the absence of the reverting tone has not been a positive indication. It has been a practice in certain exchanges to ground the "private", as 13, (or in the parlance of the art, "private normal") of the defective 125

line. This condition is to all operative purposes a false busy condition on the defective line and all connectors engaging it (but not seizing it) will project a "busy tone" or 5 tone indicative of a normal busy condition to the calling party. The calling party may thereafter attempt to reach the desired line many times, oblivious of the true condition and occupying the exchange equipments to 10 no effective purpose, aside from the annoyance phase of the situation. The present invention, as adverted to in paragraph "c" at the outset, contemplates that a specific tone or sound be projected to the calling 15 party as a function of the connector to index the true condition, occasioned by an open line state. This condition may be incident to the defectiveness, or the line may be purposely opened as stated by an 20 attendant to prevent its use or to cause it to project the specific out-of-order tone if seized, or for other reasons.

So, if the calling connector engages and seizes a bank contact set, the line thereof 25 presenting the open condition assumed, when relay H actuates, occasioning the seizure, the circuit described as transparent from alternating current source 79 through the signal device at telephone set Q is not established and therefore the primary energization of relay G will not take place to cause 30 it to actuate and lock as hereinbefore set forth. Thus, the current from signaling current source 88 will not be applied to 35 working contact 82, and the armature 97 on relay G will remain normally resting on contact 99. Ground-seeking out-of-order tone on conductor 89 is therefore applied to working contact 90 and to engaged armature 91, armature 92, resting contact 93, armature 94, working contact 95, conductor 96, armature 97, resting contact 99, conductor 57, conductor 58 and over the path 40 before described including the calling telephone set P to grounded battery, will apprise the calling party of the out-of-order 45 condition of the called line.

Assuming that there are no conductors leading from bank terminals 17, 18 and 20. 50 That is, there are no conductors leading to a working line from said 17 and 18 nor does said 20 lead to a source of grounded battery. The condition is thus that of a "dead" or unconnected line. The functioning 55 of the connector of the present invention under the condition of its seizing a set of dead bank terminals, wherein it applies a specific tone indicative of the state of the called bank number and audible to the 60 calling party has been adverted to at the outset under paragraph "b", wherein this specific tone is termed "a dead-line tone."

In certain installations the conductor as 65 referred to hereinbefore as leading to the line cut-off relay is permanently con-

nected regardless of whether a subscriber's line is connected from the bank contact set or not. This condition would vitiate the feature appertaining to the dead-line-tone. However, it is practicable to disassociate the 70 conductors corresponding to 13 of all the bank terminal sets not operatively connected to lines, so the connector will then apply the dead-line tone as contemplated upon it seizing the dead bank terminal set. Again, 75 in certain installations (and as contemplated in my application for United States Letters Patent, Serial No. 138,149, filed December 21, 1916) the conductors corresponding to 13 are disassociated from all the bank contact sets not operatively connected to lines, so the connector will then apply the dead-line tone as contemplated, upon it seizing the dead bank contact set. The operation 80 is as follows:—When wiper 19 engages bank contact 20 upon which no battery potential (nor ground potential) exists the connector 85 will seize. That is, the private magnet will deactuate and admit the sideswitch wipers to move into the third position respectively 90 and relay H will actuate as before described. However, in this instance, since no circuit path is closed through the winding of relay E, it (relay E) will not be energized and 95 actuate and therefore its armature 91 will 100 continue to rest on contact 127. Also, since there is no external signaling path between bank contacts 17 and 18, due to the assumed condition, no circuit path from ground-seeking alternating current source 79 will 105 ensue, and therefore relay G will not be primarily energized and caused to actuate. The condition as now presented to current source 79 is the same as under the assumed condition as fully discussed in reference to 110 paragraph "c" bearing in mind that in the present instance relay E is incapacitated against actuation by reason of the open condition of conductor 13. At this juncture 115 relays A, B and H are actuated. The ground-seeking dead-line tone on conductor 128 leading to resting contact 127 applies the said tone to armature 91, armature 92, 120 its resting contact 93, armature 94, its working contact 95, conductor 96, armature 97, resting contact 99, conductors 57 and 58, and thence over the path including the calling telephone set P described in connection with the cut-in tone applied from conductor 57. The calling party discerns 125 the tone indicative that the bank number representing the called line is unconnected and is therefore a so-called "dead-line."

It is thus clear that the state of relay E 130 determines which tone will be projected audible to the calling party, and further, that the state of said E will be determined by the state of the bank contact 20 engaged by the wiper 19. That is to say, assuming the circuit between bank contacts 17 and 18

open if bank contact 20 has ground potential on it, or is free of battery or ground potential, relay E will remain inert and the dead-line tone on conductor 128, and not the out-of-order tone on conductor 89, will be adapted to be applied, audible to the calling party. It follows, also, that if the circuit between bank contacts 17 and 18 are open, and if bank contact 20 has battery potential on it, relay E will actuate and the out-of-order tone on conductor 89, and not the dead-line tone on conductor 128 will be adapted to be applied, audible to the calling party.

15 It is clear, now, that if switch-arm 129 is rotated into engagement with contact-point 130 the winding of relay E will be short-circuited and the said relay will be incapacitated against being energized and attracting 20 its armature 91 against its working contact 90. Therefore, (with winding of relay E short-circuited) regardless of the state of bank contact 20 (still assuming the external circuit between bank contacts 17 and 18 to be 25 open) dead-line tone on conductor 128, and not the out-of-order tone on conductor 89 will be adapted to be applied over the described circuit path, audible to the calling party. Thus, in effect, relay E has been removed and the dead-line tone will be projected, audible to the calling party if the connector seizes a dead line (one having the telephonic circuit open and the private normal open), or if the connector seizes an out-of-order line (one having the telephonic circuit open and the private normal intact).

30 Assuming that when the wipers 15, 16 and 19 first engaged the bank contacts 17, 18 and 20 respectively, the bank contact 20 was 35 grounded. That is, had ground potential thereon (together with its multiple) in lieu of battery potential applied through line cut-off relay 14, the line being "busy". This ground condition on bank contact 20 40 may be resultant from a seizure by a connector at a multipled bank contact set, or due to the called telephone having initiated a call or because an exchange attendant has placed a ground (sometimes termed a false 45 busy) on it to guard it against seizure for some reason.

50 From foregoing descriptions it is clear that at the instant the wipers engage (but not seize) the bank contacts of a called line 55 the relay C is attracted. Also, the private magnet will be in an actuated condition because thereof and that the relay C will not in any event retract until the expiration of its period after the said engagement. So, 60 in the present assumed instance, the ground encountered by wiper 19 on bank contact 20 will be communicated over conductor 72, series winding of relay E, conductor 70, sideswitch wiper 48 in second position, conductor 131, resting contact 132, make-before-

break spring 133, winding of relay J, conductor 134, resting contact 135, make-before-break spring 46 of relay C, conductor 47 to the winding of the private magnet. It is clear that the described circuit is established 70 to contact 135 only, at the instant of engagement of wiper 19 with bank contact 20, because relay C is actuated at that instant and will not deactivate until its period expires, the contact 135 being therefore disassociated. When the relay C deactuates, make-before-break spring 46 engages resting contact 135 before armature 45, disassociates from spring 46. Thus, there is no lapse of 75 ground as applied to conductor 47 and the private magnet will remain energized and attracted, restraining the sideswitch wipers 44 and 48 from moving from the second to the third position respectively. The new ground path from the spring 46 includes the 80 series winding of relay J, causing said relay J to energize and actuate when relay C deactuates and spring 46 becomes rested on contact 135. Incident to relay J actuating off-normal ground on spring 103 applied to spring 102, conductor 120, conductor 136, armature 137 and make-before-break spring 133 locks the private magnet until the 85 springs 102 and 103 disengage consequent to the shaft restoring to normal, and the circuit path from disengaged contact 132 toward the wiper 19 is disassociated so the wiper 19 cannot have an operative effect upon the bank contact 20 in the event the line to which it belongs becomes disengaged. 90 Also, armature 66 of relay J attracts from 95 resting contact 67 and thereby disassociates the rotary magnet so in the event open impulses are sent from the calling telephone set P they will have no operative effect upon the connector. Also, armature 138 of relay J attracts into engagement with working contact 139 consequent upon the energization 100 of relay J. Ground-seeking busy tone on conductor 140 will be applied through contact 139, armature 138 and conductor 141 to conductor 58 and thence over the calling line including the telephone set P to 105 grounded battery as before described for the cut-in tone as applied to conductor 57. The 110 calling party will discern the busy tone which is indicative of the busy state of the called line. This busy tone will be applied until the off-normal springs 102 and 103, 115 disengage under the conditions stated hereinbefore, and therefore a new call cannot be initiated through the connector until its shaft has been released to normal. This latter function will be detailed presently.

120 Assuming that the condition heretofore 125 described exists, that of the calling and the called parties being in telephonic connection and therefore the receivers of the telephone sets P and Q are off the hookswitches. In this condition of the calling and called 130

telephone sets being in telephonic relation, relays D, A, B, E, F, and H are actuated.

Assuming now that the calling party replaces the receiver on the hookswitch, opening the energizing circuit traced including the windings of relay A, causing said A to deactivate, followed by the deactivation of dependent relay B its period thereafter. Working contact 34 on relay B will be ungrounded when armature 33 retracts, thus removing ground from the release trunk 36. The connector would thus become unguarded and subject to seizure by a selector responsive to a subsequent calling party or perhaps even by a newly initiated call from the party at telephone set P were the conductor 36 not regrounded. A lapse of ground occurs as regards conductor 36 of sufficient period to permit the preceding selector N to release before the re-grounding occurs. The regrounding is effected from grounded armature 33, resting contact 143, conductor 144, spring 105, spring 104, conductor 145, armature 146 and its working contact 147 on relay D, conductor 148, series winding of relay C, conductor 43, armature 42, working contact 149, conductor 150, resistance 151 (which may be wound non-inductively on core of relay J) to grounded battery. Relay C will be energized over the latter described circuit path including its winding and it will actuate and its armature 45 will apply ground to working contact 46 and to the free winding terminal of the private magnet, causing it to actuate and cause its armature 49, leading to conductor 36 to become grounded on its working contact 50, as before described. Thus the connector becomes guarded against seizure until the energizing circuit through relay C is opened. This latter cannot occur until the called party hangs up his receiver and the release magnet caused to actuate to restore the connector, as will be clear presently.

When relay B deactuates, incident to the calling party hanging up his receiver, its armature 152 will engage resting contact 153. Relay F being actuated, its armature 154 engages its working contact 155. Thus, a circuit now exists from ground-seeking last party tone conductor 156, through contact 155, armature 154, conductor 157, contact 153, armature 152, conductors 158 and 159 to conductor 58 and over the called line and through the telephone set Q (with its receiver still off the hook) and back over the described telephonic path to conductor 63 and through the upper winding of relay D to grounded battery as well as to other ground paths, effecting a specific tone audible to the called party, indicative that the calling party has hung up his receiver, whereupon he may forthwith hang up also to restore the engaged link equipments into

service. This function has been adverted to under paragraph "e" at the outset. Hanging up the called telephone receiver at this juncture opens the described energizing circuit of relay D, causing said relay 76 D to deactivate. An energizing circuit can now be traced from grounded armature 33 on relay B, its resting contact 143, conductor 144, springs 105, spring 104, conductor 145, armature 146 on relay D, its resting 75 contact 160 to the free winding terminal of the release magnet (designated Rlse. M.), causing the release magnet to actuate, restoring the connector to normal. The condenser 161 and grounded resistance 162 shown 80 at the free winding terminal of the release magnet is a well known combination to suppress excessive sparking at contacts included in the circuit path at the instant of their opening the energized path. The condenser 85 163 and grounded resistance 164 has a similar object and are therefore not directly operative elements of the connector.

Assuming, again, the condition of the calling and called telephone sets being in 90 telephonic relation, and further that the party at called telephone set Q replaces the receiver on the hookswitch, opening the energizing circuit traced including the windings of relay D, causing said relay D to 95 deactivate. A circuit now exists from ground-seeking last-party tone on conductor 156, contact 155, armature 154, conductor 157, resting contact 165 and armature 166 on relay D, conductors 158 and 159 to 100 conductor 58 and over the calling line and through the telephone set P (with its receiver still off the hook) and back over the described telephonic path to conductor 63 and through the upper winding of relay D 105 to grounded battery, as well as to other ground paths, effecting a specific tone audible to the calling party, indicative that the called party has hung up his receiver whereupon he may forthwith hang up to restore 110 the connector and also to restore the engaged link equipments into service. Hanging up the calling telephone receiver at this juncture opens the described energizing circuit of relay A, causing said relay A, and 115 its dependent relay B to deactivate in sequence. An energizing circuit can now be traced from grounded armature 33 of relay B, its resting contact 143, conductor 144, spring 105, spring 104, conductor 145, armature 146 of relay D, its resting contact 160 to the winding of the release magnet, causing the release magnet to actuate, as before stated, to restore the connector to normal.

From the foregoing it is clear that the connector will not be released unless both the calling and called parties hang up their receivers, and further, that the connector is guarded against seizure until released. 130

This function in connectors is not new. However, through the agency of my novel circuits the new function of projecting a specific tone audible to the last party hanging up, incident to the first party hanging up, is accomplished as set forth.

It will be evident to those skilled in the art that modifications of the present invention are possible without departing from the scope thereof. For example, the grounded alternating source 79 may be a source of any type of current capable of effecting the actuation of relay G under the circuit condition assumed and that alternating current source 88 may be a source of any type of current capable of effecting the actuation of the signal device at telephone set Q (or any other signal device on the line leading to said set Q) under the circuit condition assumed. Also, said independent sources 79 and 88 may be one and the same source, common to a plurality of connectors. Further, the various tone sources shown schematically may be assumed as articulate or musical tone sources. For example, in lieu of the busy tone source which may propagate a current of specific pitch, or a current of peculiar form and periodicity, a phonograph adapted to reproduce articulate words (as "Line is busy," for example) may cooperate with a telephonic transmitting circuit adapted to propagate ground-seeking telephonic currents; these currents applied to conductor 140. Likewise, a consistent phonographic telephonic combination may be substituted for each or any of the other indicated tone sources so articulate sounds, tones, words, or musical sounds will be audible in lieu of the tones as mentioned in the descriptions. Further, in lieu of the specific tone sources one only or a lesser number than shown may be used. Further, that the same character of tone may be derived from a general tone source and then applied indicative of a plurality of conditions described as indexed by specific and peculiar tones. Further, secondary interruptions may be applied to the tone-constituting current derived from a primary source so a plurality of secondary tones may be obtained, each with a distinctive audible characteristic, and these secondary tones each employed as specific tones. Thus, the tone sources shown and the interrupter devices shown are generally schematic. The tone source or sources may commonly serve a plurality of connectors.

It is also evident that the number of link elements preceding the connector may be varied to suit exchange conditions or the number of numerical orders in the telephone numbers, and, in fact, the type of the connector may be modified in means of control, general functioning and form, either as an

amplification or as a part only of the elements and functions set forth, all without departing from the scope of the present invention.

Having thus described a form of my invention, illustrative of its use and operation,

I claim:

1. In a telephone system a calling and a called line, switches including a connector having coordinate wiper movement forming a temporary train between the calling line and the called line, means for controlling the selective movement of the switches, and further means in the connector for automatically transitorily projecting a tone audible along the calling line consequent to and following the first selecting movement of the connector.

2. In a telephone system a calling and a called line, switches including a connector forming a temporary train between the calling and the called line, means for controlling ordinate movement of the switches successively, and further means in the connector for automatically transitorily projecting a tone audible along the calling line following each completed ordinate movement of the connector.

3. In a telephone system a calling line and switches including a connector for forming a temporary train, means for controlling the switches including directional movement of the connector, and means in the connector for automatically transitorily applying a tone to the talking path thereof consequent to the completion of a directional movement.

4. In a telephone system a connector which will move responsive to control means, an automatic means in the connector to effect a transitory current change constituting sound in the talking circuits of the connector consequent to the completion of the movement.

5. In a connector for selecting an accessible line controlled remotely, an automatic means for causing a transitory audible evidence in its talking circuits that it functioned responsive to the controlling agency.

6. In a connector which will move vertically in response to a first series of impulses from a sending device and to move horizontally in response to a second series of impulses from the sending device, a tone source, and means in the connector for automatically transitorily projecting the tone to its talking conductors consequent to the completion of each said movement.

7. A selective switch for telephone systems comprising a side switch, and means for automatically transitorily connecting an audible signal to the talking conductors of the switch responsive to each movement of the side switch from one position to another.

8. A connector switch for telephone sys-

130

- tems having coordinate wiper movement comprising a sideswitch, means for moving said side switch from one position to another following each directional movement of the connector, and means for automatically transitorily applying a cut-in tone to the talking conductors of the connector following each such movement of the side switch.
10. 9. In a selective switch for telephone systems, a side switch having a normal and an alternate position, a passing contact intermediate of the normal and alternate positions on the side switch, and means for automatically transitorily connecting an audible signal to the talking conductors of the switch responsive to movement of the side switch over the passing contact.
10. 9. In a telephone system, a calling telephone line, a connector for extending the connection therefrom to called bank numbers of the connector, a tone source, and means in the connector for applying the tone source to the talking circuit extending towards the calling telephone line responsive to the called bank number terminals being unconnected at the time the connector extends connection to the called bank number terminals.
10. 10. In a telephone system, a calling telephone line, switches, an impulse sending means for controlling the switches including a connector for completing a temporary connection from the calling telephone line to a called line position accessible from the connector, a tone source, and means in the connector for applying the tone source to the talking circuits of the connector when it seizes, audible along the calling line responsive to the line position selected being unconnected.
10. 11. In a telephone system, a calling and a called line, a switch for completing connection from the calling line to the terminals of the called line involving an inductively transparent talking path and a closed private path, a first and a second tone source, and means made operative consequent to seizing the terminals if either the talking path or the private conductor is open whereby if the talking path presents an open condition the said first tone source will be applied to the calling line and if the private conductor is open the said second tone source will be applied to the calling line.
10. 12. In a telephone system, a calling telephone line, a connector for extending the connection therefrom to called bank numbers of the connector, a tone source, and means in the connector for applying the tone source to the talking circuit extending towards the calling telephone line responsive to the called bank number terminals not including a circuit transparent to non-direct current at the time the connector extends connection to the called bank number terminals.
14. In a telephone system, a calling telephone line, a connector for completing a connection from the calling telephone line to a called line position of the connector, a tone source, and means in the connector for applying the tone source to the talking circuit of the connector audible along the calling line responsive to the line position called not including a circuit transparent to non-direct current.
15. In a telephone system, a calling telephone line, switches, an impulse sending means for controlling the switches including a connector for completing a temporary connection from the calling telephone line to a called line position accessible from the connector, a tone source, and means in the connector for applying the tone source to the talking circuits of the connector when it seizes, audible along the calling line responsive to the line position called not including a circuit transparent to non-direct current.
16. In a telephone system, a connector, lines, a calling said line leading to the connector for extending the connection to a called line, a telephone on the called said line, means in the connector for supplying current serially over the calling line, means in the connector controlled by the called telephone for reversing the direction of current supply from the connector over the calling line, and means in the connector for reducing the strength of current supplied the calling line before the reversal of current direction and augmenting the current strength subsequent thereto.
17. In a telephone system, a connector, lines, a calling telephone and a calling said line leading therefrom to the connector, the connector for extending the connection to a called said line, a telephone on the called line, means in the connector controlled from the telephones on both the calling and the called lines independently wherein an audible tone will be applied to one line if the telephone on the other line is restored to its normal position.
18. In a telephone system, lines, a calling said line leading therefrom to a switch, the switch for extending a connection to a called said line, means controlled from the called line wherein an audible tone will be applied to the calling line from the switch if the called line is first to be restored to its normal condition without disconnecting the switch from the called line, and means for sustaining the tone an appreciable period after the restoration.
19. In a telephone system, lines, a calling line, a switch for completing a connection from the calling to a called said lines, means on the calling line for controlling operation

- of the switch, means for controlling the restoration of the switch from both lines, and means for applying an audible appreciably sustained tone from the switch to either one line if the other line is restored. 5
20. In a telephone system, calling and called lines, a switch, means for completing a temporary connection between a calling and a called line including the switch, a tone source in the switch, and means controlled from either the calling or called line for applying the tone source to the other one of said lines. 10
21. In a telephone system, a calling and called lines, connector switch for completing a connection between a calling and a called line, a tone source, means controlled from either the calling or the called line for applying the tone source to the other one 20 of said lines, and means whereby the application of the said tone source to the calling line occurs forthwith upon the control being applied from the called line. 15
22. In a telephone system, calling and called lines, a switch, means for completing a connection between a calling and a called line including the switch, a tone source in the switch, and means controlled from either the calling or called line, operative only after a response has been obtained on the called line, for applying the tone source to the other one of said lines. 25
23. In a telephone system, a calling and called lines, connector switch for completing a connection between a calling and a called line, a tone source, means controlled from either the calling or the called line for applying the tone source to the other one of said lines, and means whereby the application of the said tone source to the called line occurs forthwith upon the control being applied from the calling line. 30
24. In a telephone system, a calling and called lines, connector switch for completing a connection between a calling and a called line, a tone source, means controlled from either the calling or the called line for applying the tone source to the other one of said lines, and means whereby the application of the said tone source to the called line or to the calling line occurs forthwith upon the control being applied by the other one of the lines. 35
25. In a telephone system, calling and called lines, a connector switch for completing a connection between a calling and a called line, other switches in the connection intermediate of the calling line and the connector, a tone source in the connector, and means controlled from the called line to cause the said tone source to be applied to the calling line without destroying the established connection from the calling line to the said connector switch. 40
26. In a telephone system, telephone lines, a telephone station including a receiver and a switch-hook on each of said lines, selective switches for interconnecting said lines, a tone source, and means responsive to an unstandard condition in a specific one of said switches arising from either said receivers being placed on its switch-hook while the other receiver remains off its switch-hook for automatically connecting said tone source to the line having its receiver off the switch-hook. 75
27. In a telephone system, telephone lines, a telephone station including a receiver and a switch-hook on each of said lines, selective switches for interconnecting said lines, a tone source, and means responsive to an unstandard condition in a specific one of said switches arising from either said receivers being placed on its switch-hook while the other receiver remains off its switch-hook for automatically connecting said tone source to the line having its receiver off the switch-hook, but not to the line having its receiver on its switch-hook. 80
28. In a telephone system, telephone lines, a telephone station including a receiver and a switch-hook on each of said lines, selective switches for interconnecting said lines, a tone source, and means whereby replacing and removing one of the receivers at will will cause the tone source to be applied and removed, respectively, to and from the other one of the lines. 90
29. In a supervisory system, telephone lines, a telephone station including a receiver and switch-hook on each of said lines, selective switches for interconnecting said lines, a tone source, and means whereby if one said receiver is replaced on its switch-hook the tone source will be applied effective to the other said receiver resultant thereto indicative of the condition. 100
30. In a supervisory system, telephone lines, a telephone station including a receiver and switch-hook on each of said lines, selective switches for interconnecting said lines, a tone source, and means made operative consequent to the interconnection of the lines and after both said receivers are off the switch-hooks to apply the tone source effective to the other one of said receivers only if its alternate receiver is replaced on its switch-hook. 105
31. In a telephone system, a calling and called lines, switch for completing connection between a calling and a called line, a first and a second distinctive tone sources, standard line terminal sets from which lead an inductively transparent talking pair of conductors and a private conductor leading to grounded battery, a first unstandard terminal set condition wherein the talking conductors are open and the private conductor is standard, a second unstandard terminal set condition wherein the talking conductors 115
- 120
- 125
- 130

and the private conductor are open, means for causing the standard operation of the switch if a standard set of terminals is seized, means for causing the said first tone source to be applied to the calling line if the said first set of unstandard terminals is seized, and means for causing the said second tone source to be applied to the calling line if the said second set of unstandard terminals is seized.

32. In a telephone system, a calling and called lines, switch for completing connection between a calling and a called line terminal set, a first out-of-order tone source, a second dead-line tone source, the said tone sources applying distinctively different tones, a standard line terminal set from which leads an inductively transparent talking pair of conductors and a private conductor leading over a closed path, a first unstandard terminal set condition wherein the talking conductors are open and the private conductor is standard, a second unstandard terminal set wherein the talking conductors and the private conductor are open, means for causing the standard operation of the switch if the said first set of standard terminals is seized, means for causing the said first tone source to be applied to the calling line if the first set of unstandard terminals is seized, and means for causing said second tone source to be applied to the calling line if the said second set of unstandard terminals is seized.

33. In a telephone system, a calling and called lines, switch for completing connection between a calling and a called line terminal set, a first out-of-order tone source, a second dead-line tone source, the said tone sources applying distinctively different tones, a standard line terminal set from which leads an inductively transparent talking pair of conductors and a private conductor leading over a closed path, a first unstandard terminal set condition wherein the talking conductors are open and the private conductor is standard, a second unstandard terminal set wherein the talking conductors and the private conductor are open, means for causing the standard operation of the switch if the said first set of standard terminals is seized, means for causing the said first tone source to be applied to the calling line if the first set of unstandard terminals is seized, and means for causing said second tone source to be applied to the calling line if the said second set of unstandard terminals is seized, whereby the calling party will be audibly apprised of the operative condition of the set of line terminals seized.

34. In a telephone system, a calling and called lines, switch for completing connection between a calling and a called line terminal set, a first out-of-order tone source, a second dead-line tone source, the said tone

sources applying distinctively different tones, a standard line terminal set from which leads an inductively transparent talking pair of conductors and a private conductor leading over a closed path, a first unstandard terminal set out-of-order condition wherein the talking conductors are open and the private conductor is standard, a second unstandard terminal set dead-line condition wherein the talking conductors and the private conductor are open, means for causing the standard operation of the switch if the said set of standard terminals is seized, means for causing said first tone source to be applied to the calling line if a said first set of unstandard terminals is seized, and means for causing said second tone source to be applied to the calling line if the said second set of unstandard terminals is seized.

35. In a telephone system, a calling and called lines, switch for completing connection between a calling and a called line terminal set, a first out-of-order tone source, a second dead-line tone source, the said tone sources applying distinctively different tones, a standard line terminal set from which leads an inductively transparent talking pair of conductors and a private conductor leading over a closed path, a first unstandard terminal set out-of-order condition wherein the talking conductors are open and the private conductor is standard, a second unstandard terminal set dead-line condition wherein the talking conductors and the private conductor are open, means for causing the standard operation of the switch if the said set of standard terminals is seized, means for causing said first tone source to be applied to the calling line if a said first set of unstandard terminals is seized, and means for causing said second tone source to be applied to the calling line if the said second set of unstandard terminals is seized whereby the calling party will be audibly apprised of the operative condition of the line terminal seized.

36. In a telephone system, a calling and called lines, switch for completing connection between a calling and a called line terminal set, a first out-of-order tone source, a second dead-line tone source, the said tone sources applying distinctively different tones, a standard line terminal set from which leads an inductively transparent talking pair of conductors and a private conductor leading over a closed path, a first unstandard terminal set out-of-order condition wherein the talking conductors are open and the private conductor is standard, a second unstandard terminal set dead-line condition wherein the talking conductors and the private conductor are open, means for causing the standard operation of the switch if the said set of standard terminals

is seized, means for causing said first tone source to be applied to the calling line if the said first set of unstandard terminals is seized, and means for causing said second tone source to be applied to the calling line if the said second set of unstandard terminals is seized.

37. In a telephone system, calling and called lines, switch for completing connection between a calling and a called line terminal set, a first out-of-order tone source, a second dead-line tone source, the said tone sources applying distinctively different tones, a standard line terminal set from which leads an inductively transparent talking pair of conductors and a private conductor leading over a closed path, a first unstandard terminal set out-of-order condition wherein the talking conductors are open and the private conductor is standard, a second unstandard terminal set dead-line condition wherein the talking conductors and the private conductor are open, means for causing the standard operation of the switch if the said set of standard terminals is seized, means for causing the said first tone source to be applied to the calling line if the said first set of unstandard terminals is seized, and means for causing said second tone source to be applied to the calling line if the said second set of unstandard terminals is seized whereby the said standard condition or either said unstandard condition will be audibly indexed by a specific one tone along the calling line upon any said set of terminals being connected with in completing a call.

38. In an electrical testing system, calling and called lines, a connector switch for completing connection from a calling to a called line terminal set, a first out-of-order tone source, a second dead-line tone source, the said tone sources applying distinctively different tones, a standard line terminal set from which leads an inductively transparent talking pair of conductors constituting a subscriber's telephone line and an auxiliary private conductor leading over a closed path, a first unstandard terminal set constituting an out-of-order condition wherein the talking conductors are open and the private conductor is standard, a second unstandard terminal set constituting a dead-line condition wherein the talking conductors and the private conductor are open, means for causing the standard operation of the connector under control of the calling line if the said set of standard terminals is seized, means for causing said first tone source to be applied to the calling line if the said first set of unstandard terminals is seized, and means for causing said second tone source to be applied to the calling line if the said second set of unstandard terminals is seized.

39. In an electrical testing system, calling

and called lines, a connector switch for completing connection from a calling to a called line terminal set, a first out-of-order tone source, a second dead-line tone source, the said tone sources applying distinctively different tones, a standard line terminal set from which leads an inductively transparent talking pair of conductors constituting a subscriber's telephone line and an auxiliary private conductor leading over a closed path, a first unstandard terminal set constituting an out-of-order condition wherein the talking conductors are open and the private conductor is standard, a second unstandard terminal set constituting a dead-line condition wherein the talking conductors and the private conductor are open, means for causing the standard operation of the connector under control of the calling line if the said set of standard terminals is seized, means for causing said first tone source to be applied to the calling line if the said first set of unstandard terminals is seized, and means for causing said second tone source to be applied to the calling line if the said second set of unstandard terminals is seized whereby upon the seizing operation of the connector ensuing a specific one tone will be applied audible on the calling line depending upon whether the standard condition is encountered, or whether either said unstandard condition is encountered.

40. In an electrical testing system, calling and called lines, a connector switch for completing connection from a calling to a called line terminal set, a first out-of-order tone source, a second dead-line tone source, a third normal-operation tone source, the said tone sources applying distinctively different tones, a standard line terminal set from which leads an inductively transparent talking pair of conductors constituting a subscriber's telephone line and an auxiliary private conductor leading over a closed path, a first unstandard terminal set constituting an out-of-order condition wherein the talking conductors are open and the private conductor is standard, a second unstandard terminal set constituting a dead-line condition wherein the talking conductors and the private conductor are open, means for causing the standard operation of the connector under control of the calling line if the said set of standard terminals is seized and to apply said third tone source to the calling line, means for causing said first tone source to be applied to the calling line if the first set of unstandard terminals is seized, and means for causing the said second tone source to be applied to the calling line if the said second set of unstandard terminals is seized.

41. In an electrical testing system, calling and called lines, a connector switch for completing connection from a calling to a called line terminal set, a first out-of-order tone

- source, a second dead-line tone source, a third normal-operation tone source, the said tone sources applying distinctively different tones, a standard line terminal set from which leads an inductively transparent talking pair of conductors constituting a subscriber's telephone line and an auxiliary private conductor leading over a closed path, a first unstandard terminal set constituting an out-of-order condition wherein the talking conductors are open and the private conductor is standard, a second unstandard terminal set constituting a dead-line condition wherein the talking conductors and the private conductor are open, means for causing the standard operation of the connector under control of the calling line if the said set of standard terminals is seized and to apply said third tone source to the calling line, means for causing said first tone source to be applied to the calling line if the first set of unstandard terminals is seized, and means for causing the said second tone source to be applied to the calling line if the said second set of unstandard terminals is seized whereby upon the seizing operation of the connector ensuing a specific one tone will be applied audible on the calling line depending upon whether the standard condition is encountered, or whether either said unstandard condition is encountered.
42. In an electrical testing system, calling and called lines, a connector switch for completing connection from a calling to a called line terminal set, an alternatively functioning signal mechanism, a first out-of-order signal control means, a second dead-line signal control means, a third normal operation signal control means, the said signal control means each causing distinctively different signal manifestations, a standard line terminal set from which leads an inductively transparent talking pair of conductors constituting a subscriber's telephone line and an auxiliary private conductor leading over a closed path, a first unstandard terminal set constituting an out-of-order condition wherein the talking conductors are open and the private conductor is standard, a second unstandard terminal set constituting a dead-line condition wherein the talking conductors and the private conductor are open, means for causing the standard operation of the connector under control of the calling line if the set of standard terminals is seized and to apply said third control means to the said signal mechanism if the first set of unstandard terminals is seized, and means for causing said second control means to be applied to the said signal mechanism if the second set of unstandard terminals is seized whereby upon the seizing operation of the connector ensuing a specific functioning of the signaling mechanism will be manifested depending upon whether the standard condition is encountered, or whether either said unstandard condition is encountered.
43. In an electrical testing system, calling and called lines, a connector switch for completing connection from a calling to a called line terminal set, an alternatively functioning signal mechanism, a first out-of-order signal control means, a second dead-line signal control means, a third normal operation signal control means, the said signal control means each causing distinctively different signal manifestations, a standard line terminal set from which leads an inductively transparent talking pair of conductors constituting a subscriber's telephone line and an auxiliary private conductor leading over a closed path, a first unstandard terminal set constituting an out-of-order condition wherein the talking conductors are open and the private conductor is standard, a second unstandard terminal set constituting a dead-line condition wherein the talking conductors and the private conductor are open, means for causing the standard operation of the connector under control of the calling line if the set of standard terminals is seized and to apply said third control means to the said signal mechanism if the first set of unstandard terminals is seized, and means for causing said second control means to be applied to the said signal mechanism if the second set of unstandard terminals is seized.
44. In a telephone system, a line and terminating connecting switch, called lines each including a normally closed inductive current path, means for operating the switch for extending a connection from the first said line to a said called line, a tone source, a source of inductive current, and means automatically applied responsive to the switch being connected to a called line presenting an open path to the inductive current for applying the tone source to the first said line.
45. In a telephone system, a line and terminating connecting switch, a called line accessible from the switch including a signal device in a normally closed circuit path to signaling current, means for operating the switch for extending a connection from the first said line to a said called line, a tone source, a source of signaling current effective to the signal device, and means automatically applied responsive to the switch being connected to the called line only if the called line presents an open path to the signaling current for applying the tone source to the first said line.
46. In a telephone system, a line and terminating connecting switch, a normally operative called line accessible from the switch, means for operating the switch for extending a connection from the first said line to

- 5 a said called line, a tone source, and means automatically effective consequent to the switch connecting to the called line only if the called line is then not normally operative 70
 5 for applying the tone source to the first said line.
- 13 47. In a telephone system, a line and terminating connecting switch, a bank position of the switch for a connected normally operative called line, a bank position of the switch for a connected non-operative called line, a tone source, means for operating the switch into connection with either bank position at will, and means dependent upon the switch being operated into connection with only the non-operative line for thereupon applying the tone source to the first said line. 75
- 29 48. In a telephone system, a line and terminating connecting switch, a bank position accessible from the switch for a connected normally operative called line, a bank position accessible from the switch having no operative connections, a tone source, means 80
 25 for operating the switch into connection with either bank position at will, and means automatically effective dependent upon the switch being operated into connection with only the second said bank position for applying the tone source to the first said line. 85
- 35 49. In a telephone system, a line and terminating connecting switch, a first bank position accessible from the switch for a connected normally operative called line, a second bank position accessible from the switch having no operative connections, a third bank position accessible from the switch for a connected normally non-operative called line, first and second tone 90
 40 sources; means for operating the switch into connection with any said bank positions, and means dependent upon whether the switch is operated into connection with the second or the third bank position for automatically applying the first or the second tone source to the first said line respectively. 95
- 50 50. In a telephone system, a line and terminating connecting switch, a plurality of idle bank positions accessible from the switch, each said bank position manifesting a different operative condition, a plurality of tone sources, each tone source corresponding to a said operative condition, means for operating the switch into connection with any said bank position, and means dependent upon the bank position connected with by the switch for automatically applying the corresponding said tone to the first said line. 100
 55
- 60 51. In a telephone system, a calling line and terminating connecting switch, called lines each including a normally closed inductive current path, a signal device connected to a talking conductor of the calling line, a signaling current source for opera- 105
 65
- tively affecting the signal device, a source of inductive current for application to a line called, means for operating the switch to extend a connection from the calling line to a called line, and means automatically applied dependent upon the switch connecting to a called line presenting an open path to the inductive current for applying the signal current source to the calling line operatively effective to the signal device. 110
52. In a telephone system, a calling line and terminating connecting switch, a normally operative idle called line accessible from the switch, a signal device connected to a talking conductor of the calling line, means for operating the switch to extend the calling line to the idle called line, and means in the switch automatically effective consequent to the switch connecting to the idle called line only if the called line is then not normally operative for operatively affecting the signal device. 115
53. In a telephone system, a calling line, switches, a normally operative idle called line accessible from one of said switches, means for extending the calling line through the said switches as links to the called line, a signal device connected in bridge of the talking conductors of the calling line, and means in the switches automatically effective consequent to the switch connecting to the idle called line only if the idle called line is then not normally operative for operatively affecting the signal device. 120
54. In a telephone system, a calling line, switches, a normally operative idle called line accessible from one of said switches, a signal device differently responsive connected to the calling line, signaling current for differently affecting the signal device, means for extending the calling line through the said switches as links to the idle called line, and means automatically applied dependent upon the switch connecting to the idle called line presenting an abnormally inoperative condition and also upon the character of the inoperative condition for applying the signaling current for operatively effecting one or another operation of the signal device, the effective operation of the signal device being indicative of the character of the inoperative condition of the called line. 125
55. In a telephone system, a calling line and terminating connecting switch, a normally operative idle called line presenting an inductive closed path accessible from the switch, a signal device on the called line, a signal device on the calling line, an inductive character testing current source for operatively non-effective application to the signal device on the called line but operatively effective to the signal device on the calling line, a signaling current source for application to the called line operatively ef- 130

fective to the signal device on the called line, means for operating the switch to extend the calling line into connection with the idle called line, and means whereby dependent upon the idle called line being normal when connected to the testing current will be operatively effective to the signal device on the calling line.

56. In a telephone system, a calling line and terminating connecting switch, a telephone on the calling line, a normally operative idle called line presenting an inductive closed path accessible from the switch, a signal device on the called line, an inductive character testing current source for operatively non-effective application to the signal device on the called line but effective to the telephone on the calling line, a signaling current source for application to the called line operatively effective to the signal device on the called line, means for operating the switch to extend the calling line into connection with the idle called line, and means whereby dependent upon the called line being normal when connected to the testing current will be operatively effective to the telephone on the calling line.

57. In a telephone system, lines, a switch for effecting connection from a calling to a called said line, means for supplying current over a path including the calling line, a resistor, means for including the resistor in the path including the calling line, means for reversing the direction of current traversing the calling line without excluding the resistor, and automatically applied means effective for thereafter excluding the resistor.

58. In a telephone system, lines, a switch for effecting connection from a calling to a called said line, means for supplying current over a path including the calling line, a resistor, automatically applied means for including the resistor in the path including the calling line, means manually controlled from the called line for reversing the direction of current traversing the calling line without excluding the resistor, and automatically applied means effective for thereafter excluding the resistor.

59. In a telephone system, lines, a switch for effecting a connection from a calling line to a called said line, means for supplying current over a path including the calling line, a resistor, means controlled over the calling line for including the resistor in the path of the calling line, and means controlled over the called line for excluding the resistor.

60. In a line testing system, lines, a switch for effecting connection from a calling to a called said line, means for supplying current over a path including the calling line, a resistor, means for including the resistor in the path including the calling line to attenuate the current strength traversing the

calling line, and automatically applied means dependent upon the called line being normally operative when connected to for effecting the operation of the second said means.

61. In a line testing system, lines, a switch for effecting connection from a calling to a called said line, means for applying current over a path including the calling line, a resistor, means for including the resistor in the path including the calling line to attenuate the current strength traversing the calling line, and automatically applied means dependent upon a specific open conductive path condition of the called line when connected to for effecting the operation of the second said means.

62. In a line testing system, lines, a switch for effecting connection from a calling to an idle called said line, means for supplying current over a path including the calling line but exclusive of the called line, a resistor, a relay, and means including the relay for including the resistor in the calling line path to alter the value of the current supplied over the calling line automatically applied consequent upon a specific open conductive path condition of the called line when connected to.

63. In a line testing system, lines, a switch for effecting connection from a calling to an idle called said line, means for supplying current over a path including a talking conductor of the calling line, a resistor, a relay, and means including the resistor and the relay for altering the value of the current supplied over the calling line automatically applied consequent upon the called line presenting a closed inductive path and an open conductive path when connected to.

64. In an automatic telephone system, lines, a switch for effecting connection from a calling to a called said line, means for directly operating the switch to effect the said connection controlled over the calling line means for supplying current over a path including the calling line talking conductors in series, a resistor, means including the resistor for altering the value of the current supplied over the calling line, means automatically applied consequent upon the called line presenting a closed inductive path and an open conductive path when connected to for effecting the operation of the third said means, and means controlled over the called line for reversing the direction of current traversing the calling line.

65. In an automatic telephone system, lines, a switch for effecting connection from a calling to a called said line, means for directly operating the switch to effect the said connection controlled over the calling line, means for supplying current over a path including a conductor of the calling line, a resistor, means including the resistor for altering the value of the current sup-

- plied over the calling line conductor, means automatically applied consequent upon the called line presenting a closed inductive path and an open conductive path 5 when connected to for effecting the operation of the third said means, and means controlled over the called line for reversing the direction of current traversing the calling line.
- 10 66. In an automatic telephone system, lines, a switch for effecting connection from a calling to a called said line, means for directly operating the switch to effect the said connection controlled over the calling line, means for supplying current over a path including the calling line talking conductors in series, a resistor, means including the resistor for altering the value of the current supplied over the calling line, means 15 automatically applied consequent upon the called line presenting a closed inductive path and an open conductive path when connected to for effecting the operation of the third said means, and means controlled over the called line for reversing the direction of current traversing the calling line and for excluding the resistor.
- 15 67. In an automatic telephone system, lines, a switch for effecting connection from a calling to a called said line, means for directly operating the switch to effect the said connection controlled over the calling line, means for supplying current over a path including a conductor of the calling line, a resistor, means including the resistor for altering the value of the current supplied over the calling line conductor, means automatically applied consequent upon the called line presenting a closed inductive path 20 and an open conductive path when connected to for effecting the operation of the third said means, and means controlled over the called line for reversing the direction of current traversing the calling line and for excluding the resistor.
- 20 68. In a telephone system, a calling line, a called line, an automatic switch for selecting the called line and thereafter completing a connection from the calling line to the called line, means for notifying the party on the calling line if the selected called line is busy and barred against connection with, means for notifying the party on the calling line if the selected called line is idle and is 25 connected with by the switch and signaling current is being normally applied thereover by the switch, and means for notifying the party on the calling line if the selected called line is idle and is connected with by the switch regardless of said normal application of signaling current thereover.
- 25 69. In a telephone system, a connective switch, a calling line, a called line accessible from the switch, means for operating the switch into connection with the called line 30 to connect the calling line to the called line, a current source for supplying current over the calling line, means for reducing the strength of current applied over the calling line from said source responsive to said connection to the called line by the switch irrespective of the ohmic resistance included in a talking conductor of the called line, and means controlled over said conductor responsive to a manual operation for restoring the 35 strength of current on the calling line without destroying the connection.
- 30 70. In a telephone system, a connective switch, a calling line, a called line accessible from the switch, means for operating the switch into connection with the called line to connect the calling line to the called line, a current source for supplying current over the calling line, a current source for supplying current over the called line, means for 40 altering the strength of current applied over the calling line from first said source responsive to specific condition of the connected called line, and means controlled by the current applied over the called line for 45 restoring the strength of current on the calling line without destroying the connection.
- 35 71. In a telephone system, a connective switch, a calling line, a called line accessible from the switch, means for operating the switch into connection with the called line to connect the calling line with the called line, a source of direct current for the calling line, a source of direct current for the called line, means for altering the strength 50 of current applied over the calling line from first said source responsive to specific condition of the connected called line, and means controlled over the called line by its 55 said current for restoring the strength on the calling line while maintaining the connection.
- 40 72. In witness whereof, I hereunto subscribe my name this 21st day of October A. D., 1920.
- 45

HERBERT M. FRIENDLY.
